(57) **CLAIM**

The ornamental design for a pair of shorts with a bottle opener with pocket, as shown and described.

DESCRIPTION

FIG. 1 is an isometric view of my new design showing a pair of shorts with a bottle opener outside of a bottle opener pocket.

FIG. 2 is a front view of my new design showing a pair of shorts with a bottle opener inside a bottle opener pocket.

FIG. 3 is a side view of my new design showing a pair of shorts.

FIG. 4 is a side view of my new design showing a pair of shorts with a bottle opener inside a bottle opener pocket.

FIG. 5 is a top view of my new design showing a pair of shorts with a bottle opener inside a bottle opener pocket.

FIG. 6 is an isometric view of my new design showing a pair of shorts with a bottle opener inside a bottle opener pocket.

FIG. 7 is a front view of my new design showing the bottle opener removed from bottle opener pocket for easier illustration. The broken lines in FIG. 7 represent stitching which is unclaimed subject matter; and,

FIG. 8 is a back view of my new design showing the bottle opener removed from bottle opener pocket for easier illustration. The broken lines in FIG. 8 represent stitching and a snap each of which is unclaimed subject matter.

The broken lines shown in the Figures are included for the purpose of illustrating portions of a pair of shorts with bottle opener with pocket and form no part of the claimed design.
